UNITED STATES PATENT OFFICE.

JOSEPH C. SOEMER, OF NEWARK, NEW JERSEY.

HORN BASE.

Application filed May 5, 1924. Serial No. 711,930.

To all whom it may concern:

Be it known that I, JOSEPH C. SOEMER, citizen of the United States, residing at Newark, in the county of Essex and State of New Jersey, have invented certain new and useful Improvements in Horn Bases, of which the following is a specification.

This invention relates to horn base constructions for radio receiving sets, and belongs to that class or type of sound amplifying contrivances comprising hollow bodies of greater or less length, of which the cross-sectional area, usually circular increases gradually from one end to the open trumpet mouth thereof, and are termed loud speakers.

An object of this invention is the production of a tone resounder or intensifier of the general character stated, having parts of special structure and disposition, including a base comprising divisional portions fashioned with spirally arranged and continuously enlarging channels forming together a sound passage and whereby a considerable increase of length is attained beyond that usual in such articles, and by which it is believed the harshness and often unnatural and partially discordant quality of reproduced music, whether vocal or instrumental, are eliminated and the composition or song or whatsoever it may be is rendered very distinct and agreeable.

In the accompanying drawings the preferred shape and location of the various parts or members are illustrated, and Fig. 1 represents a top plan view partly broken away to disclose the spiral channel. Fig. 2 is a side view. Fig. 3 is a plan view of the holder ring applied to the top of a telephone earpiece when used in this invention. Fig. 4 is a section of the ring holder on broken line 4-4 of Fig. 3. Fig. 5 is a view looking directly downward into the telephone seating chamber of this invention, and showing the holding ring in position in the chamber. Fig. 6 is a horizontal section of the telephone seating chamber on the broken line 6-6 of Fig. 7, showing the adjustable ring and springs arranged to act upon the side wall of the telephone to position the same on the bottom of the chamber. Fig. 7 is a vertical section of the chamber including the adjustable members illustrated in Fig. 6. Fig. 8 is a side view partly in vertical section, showing all parts assembled, and

showing also the spiral channel in cross-section.

Throughout the drawings and description the same letter is used to refer to the same part.

The divisional portions of the base are designated by letters A and B, which are held together by the screws C let into side posts D.

That portion of the spiral channel formed in the upper portion B of the base is marked E, and the complementary portion of the channel in the lower part A of the base is referred to by the letter F. The spiral course of the channel is indicated by the broken lines in Fig. 1, and its increased length will be noted. At the larger end of the channel is the upwardly turned horn connection G, usually removable, and in this connection the horn H is supported. This invention is not confined to a horn of any shape or size.

Upon the upper base portion B there is erected a hollow cylindrical chamber J, termed for the purposes of this explanation a telephone seating chamber, as its function is to receive the telephone earpiece. It will be noted that the chamber J has in its bottom an opening j, extending downwardly and in communication with the smallest part of the spiral channel. The inner wall of the chamber J is provided with a track or interrupted screw thread K, and, considering Figs. 3, 4 and 5, it will be noted that the telephone holding ring L has on its periphery a number of spaced teeth k, and that the teeth engage the track or threads K. It will be further observed with respect to the ring L, that its annular portion is provided with the inwardly extending and slightly raised finger pieces M. After the teeth k of the ring L are in engagement with the spiral track K, the ring may be turned by placing the thumb and finger on the pieces M, so that the ring may be moved downwardly by rotating it, and brought into pressure contact with the telephone earpiece N, shown in the chamber J in Fig. 8. Thus, the function of the holding ring L is to press downwardly upon the upper surface of the earpiece N. In addition to holding the earpiece firmly down upon the bottom of the chamber, or upon the rubber washer n which may be used, it is desirable that the sound opening or center of the ear-

piece shall coincide with the opening *j* in the bottom of the chamber, which is the beginning of the spiral channel conveying the sounds to the horn *H*. This centering or positioning of the earpiece is accomplished by the revoluble ring *O* placed on the bottom of the chamber, and carrying a number of outwardly bowed springs *P*. As best shown in Fig. 6, the periphery of the ring *O* has a number of spaced recesses *Q*, and when the ring *O* is placed in the chamber care is taken to have the projections *R*, formed on the lower portion of the inner wall of the chamber, enter the recesses near corresponding ends thereof. This arrangement brings the projections *R* into contact with the bowed springs *P* near that end of each spring which is secured to the ring *O*. Now, it will be seen that by rotating the ring *O* clockwise, the projections *R* press upon the outwardly bowed parts of the springs and move their free ends inwardly into a yielding contact with the side wall of the earpiece *N*. The operation of this invention will now be understood in view of the foregoing explanation. The associated channeled components of the base afford a long gradually enlarging sound passage which renders the sounds smooth and harmonious, while the holding ring *L* and the adjustable spring-carrying ring *O*, suitably and firmly secure the earpiece in exactly the proper position in the chamber *J*, into which it is perfectly convenient to place the earpiece or to remove it, and the full volume of sound from the earpiece is sent directly into the spiral sound passage in the base.

Having now described this invention and explained the mode of its operation, what I claim is:—

1. A horn base comprising a telephone seating chamber, said chamber having an opening leading downwardly, said base composed of upper and lower portions fitting and secured together, the said portions having formed therein a spiral and gradually enlarging channel in communication with the said opening of said chamber, and the said base having an external horn connection terminating the said channel.

2. A horn base comprising a telephone seating chamber, said chamber having an opening through the bottom thereof, the said base consisting of divisional portions fitting and secured together, the said portions being constructed to form when together a spiral and gradually enlarging channel in communication with the said opening of the said chamber, and the said base having an external horn connection terminating the said channel.

3. A horn base, comprising a telephone seating chamber, said chamber having an opening through the bottom thereof, the

said base consisting of divisional portions fitting and secured together, the said portions having formed therein an elongated and gradually enlarged channel in communication with the said opening of the chamber, and the said base having an external horn connection terminating the said channel.

4. A horn base, comprising a telephone seating chamber, the said chamber being open at the top, the said base having a channel formed therein gradually enlarging and provided with an external horn connection, the said chamber having an opening in communication with the said channel, a telephone holding member arranged in the said chamber, and means carried by the inner wall of the said chamber and constructed to engage the said member in adjustable relation.

5. A horn base, comprising a telephone seating chamber, the said base having a channel formed therein gradually enlarging and provided with an external horn connection, the said chamber having an opening in communication with the said channel, the said chamber having projecting spiral threads upon its inner wall, and a telephone holding member constructed to engage the said threads whereby the member is held in releasable contact with a telephone seated in the chamber.

6. A horn base, comprising a telephone seating chamber, the said base having a channel formed therein gradually enlarging and provided with an external horn connection, the said chamber having an opening in communication with the said channel, a telephone holding member, means carried on the inner wall of the said chamber and engaging the said member whereby the member is retained in pressure contact upon a telephone in the chamber, and adjustable devices acting upon the wall of the said chamber and upon the side wall of a telephone in the chamber to position the telephone with respect to the said opening of the chamber.

7. A horn base, comprising a telephone seating chamber, the said base having a channel formed therein gradually enlarging and provided with an external horn connection, the said chamber having an opening in communication with the said channel, a telephone holding member, means carried by the inner wall of the said chamber and engaging the said member whereby the said member is retained in pressure contact upon a telephone in said chamber, springs arranged to act upon the side wall of a telephone in the said chamber, and means acting upon the springs to position a telephone in the said chamber with respect to the said opening in the chamber.

8. In a horn base, a telephone holding ring comprising an annular portion having

spaced projections on its periphery and internally projecting tongues whereby the ring may be turned by the fingers of the hand.

9. In a horn base, a telephone seating chamber having spaced internal projections near the bottom, a revoluble ring resting upon the bottom of the chamber, and springs having each one end attached to said ring and outwardly curved portions acting 25 against the said projections of the chamber wall as the ring is revolved whereby the free ends of the springs are pressed inwardly with respect to the wall of the chamber.

10. In a horn base, a telephone seating chamber having spaced internal projections near the bottom, a revoluble ring resting upon the bottom of the chamber and having spaced recesses in its periphery, the said projections of the chamber occupying the 20 said recesses of the ring, and springs having each one end attached to the said ring

and outwardly curved portions acting against the said projections of the chamber as the ring is revolved whereby the free ends of the springs are pressed inwardly 25 with respect to the wall of the chamber.

11. In a horn base, a telephone seating chamber, a sound-conveying channel having a horn connection, said chamber having an opening in communication with the said channel, an adjustable telephone holding member engaging the wall of the chamber and acting downwardly upon a telephone in the chamber, and adjustable cushioning devices arranged to act upon the side wall 30 of a telephone in the said chamber to position the telephone with respect to the said opening of the chamber.

In testimony whereof I affix my signature.

JOSEPH C. SOEMER.
